UNITED STATES PATENT OFFICE.

GEORGE EDWIN DUNSTAN, OF LORAIN, OHIO.

DOUBLE-FLANGE TRAP AND SINK.

No. 873,120.

Specification of Letters Patent.

Patented Dec. 10, 1907.

Application filed August 10, 1906, Serial No. 330,052.

To all whom it may concern:

Be it known that I, GEORGE E. DUNSTAN, a citizen of the United States, residing at Lorain, in the county of Lorain and State 5 of Ohio, have invented a new and useful Double-Flange Trap and Sink, of which the following is a specification.

The present invention relates to improvements in stench traps and slop sinks of the 10 surface type, and it relates particularly to means for preventing moisture or water from creeping or leaking out over the usual top flange of the trap or sink and passing down through the floor and disfiguring the ceiling 15 and doing other damage.

The principal object of the invention is to provide a simple and inexpensive addition to the casing of a trap in the nature of a peripheral flange just below the surface flange of 20 the casing and arranged to be embedded in the cement or asphalt of the floor, so as to dam back the moisture or water and prevent it from passing through the floor.

With this object in view, and others, as 25 will appear as the nature of the invention is better understood, the invention comprises various novel features of construction and arrangement of parts, which will be more fully described hereinafter and set forth with 30 particularity in the claims appended hereto.

In the accompanying drawing, which illustrates certain embodiments of the invention, Figure 1 is a central vertical section of a stench trap having a flange constructed in 35 accordance with the invention. Fig. 2 is a plan view thereof. Fig. 3 is a plan view of a slop sink showing the flange applied to the same. Fig. 4 is a central vertical section thereof.

40 Corresponding parts in the several figures are indicated throughout by similar characters of reference.

Referring to the drawing, 1 designates the body of a stench trap of the character disclosed in the U. S. Patent to George Dunstan, #543,617. The trap is of the surface type having a horizontal peripheral flange 2 at the upper end of the casing that is adapted to be embedded flush with the floor surface. 45 As to the internal construction of the trap, the present invention has no bearing, but relates particularly to a peripheral flange 3 extending around the casing at a point a few inches below the surface flange 2. This 50 flange is adapted to be embedded in the cement, asphalt, or other material 5, of

which the floor is constructed, and is preferably cast integral with the casing, so as to avoid the presence of a joint. Along the outer edge the flange 3 is flared upwardly so as to form an upturned rim 4, in order that the flange 3 may serve as a trough or basin. The flange, measured in a radial direction, extends somewhat beyond the periphery of the surface flange 2, so that the water or 60 moisture that passes over the periphery of the flange 2 into the floor 5 will be caught in or dammed up by the basin-like flange 3, and thus be prevented from passing down along the trap and disfiguring the ceiling and 65 causing other damage, a slight crevice being usually left between the trap and the floor by reason of the shrinkage of the cement in setting, and the liquid that would otherwise leak through or around the casing to the 70 ceiling below is intercepted, in the present instance, by the basin or trough which is larger than, and extends outwardly beyond, the upper flange. Another reason for making the lower flange larger than the top one 75 is to enable the workman to throw cement or asphalt into the lower flange and thus make a better job, the rim of the supplemental or lower flange being upturned at a point outside of or beyond the periphery of the upper 80 flange in order that the cement or other material composing the floor or setting for the trap may be thrown into the lower flange from above, the space between the upper and lower flanges forming a pocket with a 85 reduced opening between the upper flange and the upturned rim 4 through which the cement may be introduced and tamped, causing it to be very closely packed around the trap to prevent moisture or surface 90 water entering between it and the surrounding floor. The upturned rim of the lower flange in this case against the lower strata of cement crowding away from the trap as the cement above it is tamped in place. 95 The flange 3 preferably follows the outline of the flange 2, and hence is circular when applied to surface traps of the character shown in Fig. 1, or square when used in connection with slop sinks, such as that shown 100 in Figs. 3 and 4. In some cases, however, traps and sinks are round and have square flanges. In such instance, the lower flanges would also be square.

The construction of the slop sink 6 is substantially the same as those in common use, except that the same is cast with the pe-

ripheral moisture excluding flange 7. This operates and is used in the same manner as that described in connection with Figs. 1 and 2. The edge of the flange 7, instead of being shown as formed into an angular rim, is curved upwardly to produce an equivalent basin-like construction, thus illustrating that various forms may be employed.

While I have described the invention in connection with a particular kind of trap and sink, it is obvious that it may be used with other forms which possess the objectionable features that this invention is designed to overcome.

I have described the principle of operation of the invention, together with the apparatus which I now consider to be the best embodiment thereof, but I desire to have it understood that the apparatus shown is merely illustrative, and that various changes may be made, when desired, as are within the scope of the invention.

What is claimed is:—

1. A device of the character described comprising a casing having a peripheral flange surrounding its upper edge, the upper surface of the flange being flush with the upper edge of the casing, and a supplemental imperforate flange surrounding the casing immediately below the upper flange and

having a peripheral rim turned upwardly and offset outwardly beyond the periphery of the upper flange to form an enlarged basin to catch and retain the liquid leaking by the upper flange. 35

2. A trap or the like embodying a casing having an upper peripheral flange thereon, and a supplemental imperforate flange surrounding the casing below the upper flange and projecting outwardly beyond the periphery thereof and provided with an upturned surrounding rim forming a cement receiving pocket between the flanges with a contracted opening through which the cement may be introduced and tamped, the upturned peripheral rim constituting a shoulder to prevent the cement crowding away from the casing, and also forming an annular liquid receptacle surrounding it and serving to intercept liquid leaking between the outside of the casing and the surrounding floor. 40 45 50

In testimony that I claim the foregoing as my own, I have hereto affixed my signature in the presence of two witnesses.

GEORGE EDWIN DUNSTAN.
